TOY HOP-MOBILE

Bonnie Smith, Jr., Philadelphia, Pa.

Application May 28, 1954, Serial No. 30,742

Term of patent 14 years

(Cl. D34—15)

FIG. 2

Fig. 1 is a side elevational view of a toy hop-mobile, showing my new design; and

Fig. 2 is a plan view thereof.

I claim:

The ornamental design for a toy hop-mobile, substantially as shown.
